CLAIM

I claim the ornamental design for an extended scraper tool, as shown and described.

DESCRIPTION

FIG. 1 is a perspective view of the extended scraper tool according to the present design;

FIG. 2 is a right side view of the present design, the corresponding left side view being a mirror opposite thereof;

FIG. 3 is a top view of the present design;

FIG. 4 is a front view of the present design;

FIG. 5 is a rear view of the present design; and,

FIG. 6 is a bottom view of the present design.
